United States Patent Office.

JOHN A. SPOONER AND JOHN ELLERBY, OF BROOKLYN, NEW YORK.

Letters Patent No. 99,365, dated February 1, 1870.

IMPROVEMENT IN BUTTONS.

The Schedule referred to in these Letters Patent and making part of the same.

To all whom it may concern:

Be it known that we, JOHN A. SPOONER and JOHN ELLERBY, of Brooklyn, in the county of Kings, and State of New York, have invented a new and improved Button for Gloves, &c.; and we do hereby declare that the following is a full, clear, and exact description thereof, which will enable others skilled in the art to make and use the same, reference being had to the accompanying drawings, forming part of this specification.

Figure 1 represents a central section of our improved button.

Figure 2 is a plan view, partly in section, of the same.

Similar letters of reference indicate corresponding parts.

This invention relates to a new self-fastening button, which is to be applied to gloves and other articles of wearing-apparel without the use of thread, and without injury to the fabric to which it is secured.

Our invention consists in making the button of two parts, A and B, so constructed that the fabric may be secured between them, as hereinafter specified. The part A is a cap stamped out of sheet-metal, or other suitable material, *a* indicating the top and *b* the flange thereof, the latter inclining slightly inward.

The part B is somewhat smaller than A, but substantially of the same form, except that its flange *c* is bent first inward and then outward at its edge, as shown.

The button is fastened by placing the parts A and B on opposite sides of the fabric in such position that on forcing them together the fabric will be clamped or held between them, as shown in fig. 1.

When applied to gloves, that part of the button which projects from the face may be so constructed as to admit of the attachment of a chain or other analogous fastening-device.

The faces of the buttons may be otherwise ornamented or plain, as desired.

Having thus described our invention,

We claim as new, and desire to secure by Letters Patent—

A button made of two flanged parts, A B, which are connected by clamping the fabric between them, as set forth.

JOHN A. SPOONER.
JOHN ELLERBY.
